UNITED STATES PATENT OFFICE.

WILLIAM M. HURLEY, OF ROCKLAND, MASSACHUSETTS.

SHOE AND METATARSAL ARCH SUPPORT THEREFOR.

Application filed May 26, 1927. Serial No. 194,465.

This invention relates to boots and shoes having arch supporting devices incorporated therewith, and has for an object the provision of a boot or shoe having a metatarsal arch support disposed between the inner and outer soles of the shoe which is characterized by being flexible so that it can bend with the sole and thus does not materially impair the flexibility of the sole.

10 A further object of the invention is the provision of a flexible metatarsal arch support, as a new article of manufacture.

15 A yet further object of the invention is generally to improve the construction of boots and shoes and arch supports therefor.

Fig. 1 is a side elevation partly broken away to illustrate the invention.

Fig. 2 is a section along line 2—2 of Fig. 1.

Fig. 3 is a plan view of the metatarsal arch support embodying the invention.

Fig. 4 is a section along line 4—4 of Fig. 3.

Fig. 5 is a view of an inner sole on a last and illustrating the construction of the last for forming a recess in the inner sole in which 25 the arch support of Fig. 3 is received.

Fig. 6 is a plan view of the bottom of the recessed inner sole.

Fig. 7 is a longitudinal section through a modified construction of the arch support.

30 The invention is here shown as applied to a welt shoe having the upper 10, inner sole 12 and outer sole 14. The inner sole is provided with a raised portion 16 which is disposed at the forward end of the shank stiffener 18 and at one side of the ball portion 20 of the sole and in position to be under, and provide support for, the metatarsal bones of the foot. The raised portion 16 is of general ellipsoidal form with the major axis extended 35 parallel with the longitudinal axis of the sole. The raised portion is highest in the middle and slopes gradually downward to the edges where it merges with the general plane of the top of the sole.

40 The raised portion of the sole is supported by a metatarsal arch support 22 which is received under the raised portion between the inner and outer soles and over the forward end of the shank stiffener 18. The arch sup-

45 port, see Figs. 3 and 4, has generally the shape of the raised portion 16 and is of ellipsoidal form and is highest in the middle and tapers down to a thin edge at the sides. It is composed of two pieces 23 and 24, preferably of

50 leather, which are adhesively affixed to a flexible backing sheet 26 of textile fabric, and

which have opposed straight edges 28 that are closely spaced apart to provide a gap 30 in the support that permits free independent movement of each piece. The gap 30 is transversely disposed in the shoe and is in the line of the natural flexing of the sole and the arch support consequently does not restrict the flexibility of the sole in any material manner.

55 The inner sole is provided with a recess for the arch support and, at the same time, the raised portion 16, by forcing the tempered material of the inner sole into a suitably formed recess or depression 32 in the last 34.

60 In the modification shown in Fig. 7, the arch support is made of a single piece of leather 22^a shaped as in Fig. 3 and provided with a transverse notch 30^a in its top face which extends only part way through the thickness of the support, thus to provide a thin flexible section 26^a beneath the notch by which the front and rear sections of the support are integrally flexibly connected. This construction does not necessitate the use of the backing strip 26 of Fig. 4.

65 I claim:

1. A shoe having inner and outer soles and a separate metatarsal arch support disposed between the soles and in a recess in the lower face of the inner sole, said support being of general ellipsoidal shape with the major axis thereof extended generally parallel with the longitudinal axis of the shoe and being highest in the middle and tapered to a thin edge at the sides, said support being most flexible 70 along its transverse axis, which axis is located in the line of flexure of the soles.

75 2. A shoe having inner and outer soles and in separate metatarsal arch support disposed between the soles and in a recess in the lower face of the upper sole, said support being of general ellipsoidal shape with the major axis thereof extended generally parallel with the longitudinal axis of the shoe and being highest in the middle and tapered to a thin edge at 80 the sides, said support having two opposed sections flexibly connected together along the transverse axis of the support and in the line of flexure of the soles.

85 3. A shoe having inner and outer soles and a separate metatarsal arch support disposed between the soles and in a recess in the lower face of the upper sole, said support being of general ellipsoidal shape with the major axis thereof extended generally parallel with the longitudinal axis of the shoe and being highest in the middle and tapered to a thin edge at 90

the sides, said support having two opposed and spaced sections affixed to a flexible backing sheet which is adapted to flex at the space between the sections and in the line of flexure 5 of the shoe.

4. A shoe having inner and outer soles and a metatarsal arch support disposed between the soles in a recess in the lower face of the upper sole, said support having two closely spaced sections disposed in line along the longitudinal axis of the shoe and a flexible backing sheet affixed to and flexibly uniting said sections and being free to flex in the line of flexure of the soles.

15 5. A shoe having inner and outer soles and a metatarsal arch support disposed between the soles in a recess in the lower face of the upper sole underlying the metatarsal bones of the foot, said support having two closely spaced sections having straight proximate edges disposed transversely of the shoe in the line of flexure of the soles thereof, and a flexible backing sheet affixed to and flexibly connecting said sections.

25 6. A metatarsal arch support comprising an elongated body of generally ellipsoidal shape the longer axis of which is adapted to lie in the length of the shoe, said body being composed of two opposed sections composed 30 of leather, and means flexibly connecting them together along the shorter axis of said body.

7. A metatarsal arch support comprising

an elongated body composed of two opposed closely spaced sections and a flexible backing sheet affixed to and flexibly connecting said sections.

8. A metatarsal arch support comprising an elongated body composed of two opposed closely spaced sections having straight proximate edges separated by a gap, and a flexible backing sheet affixed to both sections and bridging said gap and providing a hinged connection between the sections.

9. A metatarsal arch support for boots and shoes comprising a body having a general ellipsoidal shape and adapted to be located in the shoe with its major axis parallel with the longitudinal axis of the shoe, said body being highest at the middle and tapered to a thin edge at the sides and composed of two sections which are separated by a small gap which lies along the minor axis of the body, and a flexible backing sheet affixed to both sections and bridging said gap and providing a connection between the sections which is flexible at the gap.

20 10. A metatarsal arch support comprising an elongated body the longer axis of which is adapted to lie in the length of the shoe beside the ball-portion thereof, said body having a transversely weakened middle section which permits the flexing of the body thereat.

In testimony whereof, I have signed my name to this specification.

WILLIAM M. HURLEY.
